CLAIM

The ornamental design for a workout bench, as shown and described.

DESCRIPTION

FIG. 1 is a perspective view of a workout bench according to a first embodiment and further depicting a telescoping member of the workout bench in a recessed position.

FIG. 2 is a right elevation view depicting the telescoping member of the workout bench in an extended position.

FIG. 3 is a left elevation view thereof.

FIG. 4 is a rear elevation view thereof.

FIG. 5 is a front elevation view thereof.

FIG. 6 is a top plan view thereof.

FIG. 7 is a bottom plan view thereof.

FIG. 8 is a perspective view of a workout bench according to a second embodiment and further depicting a telescoping member of the workout bench in a recessed position.

FIG. 9 is a right elevation view depicting the telescoping member of the workout bench in an extended position.

FIG. 10 is a left elevation view thereof.

FIG. 11 is a rear elevation view thereof.

FIG. 12 is a front elevation view thereof.

FIG. 13 is a top plan view thereof; and,

FIG. 14 is a bottom plan view thereof.

The broken lines in FIGS. 8-14 represent environmental structure and portions of the workout bench that form no part of the claimed design.

1 Claim, 14 Drawing Sheets
